SPARK-PLUG.

1,373,682.

Specification of Letters Patent.

Patented Apr. 5, 1921.

Application filed March 18, 1918. Serial No. 223,213.

To all whom it may concern:

Be it known that I, MAURICE P. SULLIVAN, a citizen of the United States, residing at Torrington, in the county of Litchfield and 5 State of Connecticut, have invented certain new and useful Improvements in Spark-Plugs, of which the following is a specification.

This invention relates to spark plugs and 10 comprises means whereby high tension electric current, generated by any suitable method, is caused to produce, in a highly efficient and desirable manner, ignition sparks for the purpose of firing the explosive charge in the cylinders of an internal combustion engine.

It has been found that the ordinary or usual type of spark plug is far from satisfactory when used in aeroplane engines on 20 account of the duties imposed upon it by an engine of this kind. In the case of an internal combustion engine used on an automobile the engine speed is continually varying, due to the varying load, and at only 25 short intervals of time is the full horse power of the engine required and the maximum horse power developed is not very large, while in an aeroplane engine the horse power developed is a number of times larger 30 than in an automobile engine and this horse power is being developed substantially at a constant rate for a number of hours, hence it will be readily understood that the duties imposed upon the spark plugs used in an 35 aeroplane engine are exceedingly severe and special plugs have had to be designed to meet this new and unusual condition.

It is, therefore, the object of this invention to produce a plug which will operate satisfactorily in an aeroplane engine by protecting and ventilating the insulating member or members to prevent their destruction by the severe heating and influence of the exploding gases.

Another object of my invention is to provide a plug which is comparatively simple in its construction and therefore one that will be easy and relatively cheap to manufacture.

These and other objects will be apparent after a study of the further description together with the accompanying drawing which forms a part of the specification.

In the drawing, Figure 1 illustrates a view

of my assembled plug with half of the same 55 in section.

Fig. 2 is a view of the central electrode construction, and

Fig. 3 illustrates a modified form of construction.

Referring now to the details, wherein like numbers refer to corresponding parts in the different views, 1 is a shell having threads 2 cut thereon for the purpose of screwing the shell and complete plug into the engine cylinder by means of a wrench applied to the hex portion 26. In some cases the shell 1 may have a groove 3 cut therein for the purpose of lightening the shell and increasing the heat radiating surface. The upper part 70 of the shell 1 has a chamber 4 therein, and opening outwardly from this chamber are a number of holes 5 for the purpose of ventilation. Leading from the chamber 4 toward the threaded end of the shell is a hole 75 6, tapering upward. A central electrode 7 has wound around it mica insulation 8. The application of mica 8 to the central electrode 7 is such that the mica tapers upward. Mounted on the mica 8 is a gland 9 which is 80 tapered inside to fit the mica 8 and is ground to a taper on the outside to fit the tapering hole 6. After the mica 8 and gland 9 have been assembled to the central electrode 7, the upper end of which is threaded at 10, the 85 lower end is turned off to the proper length and an electrode terminal 11 is fastened to the electrode 7 by staking the same over at 12. The electrode terminal 11 is preferably made of good heat conducting material, such 90 as copper, whereby the heat generated in the internal combustion chamber will be conveyed to the central electrode 7 and carried upward and dissipated through the holes 5 and through further means which 95 will be later described. I prefer to make the electrode 7 tapering, as indicated at 13, in order to leave as much of a chamber as possible between its inner edge and the lower end of the gland 9, furthermore, so that a 100 sharp edge 14 will be presented toward the shell 1 for the purpose of furnishing a spark gap. After the central electrode unit is put up, as in the form shown in Fig. 2, it is then slipped into the shell 1 and a spacing collar 105 15 is then applied to the upper portion of the shell. An insulator 16, preferably of porcelain, is then put on over the central

electrode 7 and the mica insulation 8 with its lower flange 17 resting upon the collar 15. The insulator 16 has a bore 18 large enough to leave a clearance space between 5 the central electrode structure and its inner walls. An air space 19 is also provided around the lower exterior or skirt portion of the insulator 16 and the spacing collar 15, which latter part may have a series of holes 10 similar to holes 5 in the shell 1; but by way of distinction I stamp these holes in the form of letters to indicate the manufacturer's name, two of such letters of the word "Splittdorf" being indicated. The insulator 15 16 may have grooves 20 therein for the purpose of giving greater radiating surface. Lockwasher 21 and cap nut 22 which engage the threads 10 on the central electrode 7 are used to draw the parts together and lock 20 them in operative position. The nut 22 may have a round end 23 for the reception of a certain type of cable terminal or it may have a screw 24 to take another type of cable terminal. From the above it will be seen that 25 by the use of a properly proportioned and ground taper fit between the shell 1 and the gland 9, I am enabled to secure a perfect gas-tight joint. The gland 9 also serves to hold the mica from expanding and from the 30 means employed a large heat radiating surface is provided.

In the modified form shown in Fig. 3, the shell 1 and the gland 9 are not made with a long taper as shown in Figs. 1 and 2 but a 35 more abrupt taper 25 is used in the manner indicated. The rest of the central electrode is the same as that shown in Fig. 2. The insulator 16 is of somewhat different shape from that shown in Fig. 1 otherwise the 40 parts of the plug shown in Fig. 3 are the same as heretofore described.

It will be understood that the form of shell or insulator or other parts may be varied considerably without departing from the 45 spirit of my invention or the scope of the appended claims.

Having thus described my invention what I claim is:—

1. In a spark plug, the combination of a shell having threads cut at one end thereof for the purpose of screwing said shell into an engine cylinder, a chamber at the opposite end and a bore tapering upward from the threaded end into said chamber, a unitary structure consisting of a central electrode with only wound mica insulation theron, a tapered metallic gland securely positioned on the wound mica and a terminal attached to the end of said central electrode, a fixed 50 distance from said gland, said unitary structure being adapted to fit within said shell in such a manner that the taper on said gland engages the tapered bore on said shell so as to give a predetermined spark gap between 55 the terminal and the shell, a spacing collar resting on the upper part of said shell, an insulator fitting over the central electrode and resting on said collar and a nut adapted to screw on to the upper part of the central electrode to draw all of said parts securely 60 into operative position, as described.
2. In a spark plug, the combination of a shell having one end threaded for the purpose of screwing said shell into an engine cylinder, and having a tapered bore extending upward from the threaded end of said shell, a metallic gland having a tapering surface adapted to fit said bore, a central electrode extending through said gland and shell but insulated entirely therefrom by 65 mica securely wrapped around said electrode and tightly fitting within the bore of said gland, said central electrode carrying a circular sparking block of good heat conducting material a definitely fixed distance from the 70 gland, a spacing collar mounted on said shell, an insulator supported on said spacing collar and means for drawing the central electrode upward to cause said gland to engage said shell and to hold the said insulator 75 and spacing collar in working position as described.
3. In a spark plug, the combination of a shell having threads cut at one end thereof for the purpose of screwing said shell into 80 an engine cylinder, a chamber at the opposite end and a bore tapering upward from the threaded end into said chamber, a unitary structure consisting of a central electrode having only wound mica insulation thereon so as to taper upwardly, a 85 metallic gland bored to fit the taper of said mica insulation and ground on its exterior surface to fit the tapered bore in said shell and a block tapering to a knife edge attached to the end of said electrode but definitely spaced away from said gland, said unitary structure being adapted to fit within 90 said shell in the manner described, a spacing collar adapted to rest on the top part of said shell and inclosing the opening of said 95 chamber, an insulator supported on said collar and having a skirt extending downward around the upper portion of the mica on 100 said central electrode and spaced apart from the wall of said collar thereby forming an air space, ventilating holes through said collar and in said shell extending into said chamber, and means engaging the upper part of said central electrode for holding all 105 of said parts securely in operative position.
4. In a spark plug, the combination of a shell having threads cut at one end thereof for the purpose of screwing said shell into 110 an engine cylinder, a chamber at the opposite end having perforated walls and a bore extending from the threaded end upwardly into said chamber, a central electrode positioned within said bore by means of a cone shaped mica wrapping carrying a metallic 115 120 125 130

gland having a bore adapted to fit said mica cone, said gland having its outer surface tapered to fit a corresponding taper on said bore, said electrode carrying at its lower end 5 a block spaced longitudinally a fixed distance from said gland and terminating in a knife edge adjacent the interior wall of said shell and tapering upwardly to form a gas space around the lower portion of said mica 10 wrapping, a porcelain insulator supported on the upper part of said shell and having a skirt extending downwardly around the upper part of said mica cone, with means for clamping the porcelain insulator in place on the shell, said means serving also to hold the central electrode in working position within said shell. 15

In witness whereof, I affix my signature.

MAURICE P. SULLIVAN.
